UNITED STATES PATENT OFFICE.

WALTER E. ROSEBRO, OF ELMHURST, CALIFORNIA.

DESIGN FOR A THREAD OR TWINE CUTTER.

SPECIFICATION forming part of Design No. 28,888, dated June 21, 1898.

Application filed March 16, 1896. Serial No. 583,470. Term of patent 14 years.

To all whom it may concern:

Be it known that I, WALTER E. ROSEBRO, a citizen of the United States, residing at Elmhurst, county of Alameda, State of California, have invented and produced a new and original Design for a Thread or Twine Cutter, of which the following is a specification, reference being had to the accompanying drawings, showing a part thereof, in which—

Figure 1 is a perspective view of my thread and twine cutter. Fig. 2 is a cross-sectional view on the line $x x$ of Fig. 1.

The leading feature of my design consists of a flat ring or band of uniform thickness throughout having a head with an ornamental stone or device set therein and a shank of substantially triangular shape in horizontal section, said shank having the walls of its three sides curved inwardly to form independent vertical edges between adjacent curved portions, and the greatest diameter of the shank being less than the width of the band. The head B is of circular form and its surrounding edge or periphery is curved, as shown.

A is the ring, which is circular in its gen-

eral contour, and B is the head, the top of which is recessed to receive an ornamental stone or device, which rises slightly above the plane of the top of the head. This head is of circular form and has a greater diameter than the shank, which connects it with the band, and its surrounding edge or periphery is rounded. Between the head and the ring is a shank C, the peculiar characteristic of which is that it has substantially a triangular form in horizontal section. The diameter of the shank is less than the width of the flat band and the walls of the three sides of the shank are made concave, thereby forming along the outer edges of adjacent grooved or concaved portions the independent vertical parallel edges or sharp angles, as shown.

Having thus described my invention, what I claim is—

The design for a thread and twine cutter substantially as shown and described.

In witness whereof I have hereunto set my hand.

WALTER E. ROSEBRO.
